UNITED STATES PATENT OFFICE.

EDWIN G. EMMERT, OF SHERDAHL, KANSAS.

RAILROAD CATTLE-GUARD.

SPECIFICATION forming part of Letters Patent No. 546,775, dated September 24, 1895.

Application filed April 2, 1895. Serial No. 544,168. (No model.)

To all whom it may concern:

Be it known that I, EDWIN G. EMMERT, a citizen of the United States, residing at Sherdahl, in the county of Republic and State of 5 Kansas, have invented certain new and useful Improvements in Railroad Cattle-Guards; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 The special object of the invention is to make a cattle-guard gate which may be automatically opened by each train as it approaches.

Figure 1 of the drawings is a plan and Fig. 20 2 a perspective view of my invention, showing it applied.

25 In the drawings, A A' represent the rails of a railway, under and between which is secured the board or plate B, from which, at one corner, uprises a post C. To the latter is hinged a gate D, extending across the track to prevent stock from passing out of a fenced field.

30 E is a crank-shaft pivoted to turn in post-bearings c c and connected by an eye e at its outer end with a double hook F, the latter being connected with an eye-rod G, made fast to the gate-stile d. The gate is held in position across the tracks by a coiled spring H, 35 one of whose ends is secured to the gate-stile d, while the other is coiled about the staple I, or any other suitable contrivance. When the force which opens the gate has ceased to operate, the tension of the spring will close it.

40 J is a pinion fast on the lower end of the

crank-shaft E and meshing with a spur-wheel K, which turns on a pivot in the board or plate B. On this spur-wheel is a fixed arm k, which extends under the track A', and on this arm is middle-riveted a plate L, with a hole l 45 near each end. In each of the holes l is secured one end of a rod M, whose other end is pivoted to the lower end of a lever N, whose upper end is struck by the wheel of each car on that side of the tracks, so as to operate 50 the train of mechanism described and open the gate. The latter is thus held open until all the train has passed, when the coil-spring retracts the gate into position across the track. I may support the rod M in a pivoted hanger 55 o, but, while preferable, that is not necessary.

I am aware that cam-blocks, vibrating cam-levers, springs, and chains over pulleys are not new in connection with hinged railroad-gates; but 60

What I claim as new is—

The combination of a post C, a gate D hinged thereto and extending across the track; a shaft E supported in bearings on the post which carries a pinion J and has a crank-arm 65 extending behind said post; an arm G secured to the gate-stile; a link F connecting arm G with the crank-arm; a spurwheel K intermeshing with the pinion J and having an arm which passes under and completely across the 70 track; tread-levers N connected to said arm; and a retracting spring secured to the gate, all substantially as shown and described.

In testimony whereof I affix my signature in presence of two witnesses.

EDWIN G. EMMERT.

Witnesses:

B. M. EMMERT,
ROSE EMMERT.
